FIG. 3

FIG. 4

Fig. 1 is a diagrammatic view of a bedspread showing my new design;

Fig. 2 is an enlarged view of the area A—B—C—D shown in Fig. 1;

Fig. 3 is an enlarged view of the area B—E—F—C shown in Fig. 1;

Fig. 4 is an enlarged view of the area E—G—H—F shown in Fig. 1; and

Fig. 5 is an enlarged cross-sectional view taken on the line 5—5 of Fig. 1.

The area J—K—L—M—H—F—C—D on the opposite side of the center line D—C—F—H is equal and opposite to the area A—B—E—G—H—F—C—D.

The design disclosed is composed of high pile chenille tufts arranged on a background of vertically extending rows of short pile chenille tufts as particularly shown in Figs. 2, 3 and 4.

The border adjacent to the fringe as shown in Figs. 2, 3 and 4 is contained within the parallel lines shown in Fig. 1.

I claim:

The ornamental design for a bedspread or similar article, substantially as shown and described.
